DESIGN FOR A PULLER HOIST

Humphrey F. Parker, Buffalo, N. Y.

Application November 19, 1946, Serial No. 134,907

Term of patent 14 years

(Cl. D41—1)

To all whom it may concern:

Be it known that I, Humphrey F. Parker, a citizen of the United States, residing at Buffalo, in the county of Erie and State of New York, have invented a new, original, and ornamental Design for Puller Hoist, of which the following is a specification, reference being had to the accompanying drawing, forming part thereof.

Fig. 1 is a side elevational view of a puller hoist, showing my new design;

Fig. 2 is a fragmentary end elevational view thereof; and

Fig. 3 is an opposite side elevational view thereof.

The characteristic features of my design reside in the portions shown by means of full lines in the drawing.

I claim:

The ornamental design for a puller hoist, as shown and described.

HUMPHREY F. PARKER.
